Application March 2, 1937, Serial No. 128,560
In Germany March 5, 1936

5 Claims. (Cl. 18—8)

Our present invention relates to the manufacture of threads.

One of its objects is a process of after-treating threads. Another object is a device for after-treating threads. Further objects will be seen from the detailed specification following hereafter.

In the manufacture of artificial materials from cellulose solutions, it is necessary to subject the threads, bands or the like, obtained by spinning to various operations for producing decomposition, washing and purification. For example, in making a viscose thread it is the general practice to pass the precipitated viscose threads or bands continuously in a long path through acid for the decomposition of the residual xanthate, then there follow washing, bleaching, further washing, soaping and like operations. The raw material is thus withdrawn in continuous working either over moving rollers or the like through long stretches of various baths or in long suspended loops through suitable immersion baths. Since in general this treatment of the threads or bands occupies a certain time, it is necessary in order to procure the desired effect on the endless travelling threads or bands frequently to provide for one stage of the treatment a bath of 10 meters and more; thus the system of after-treatment occupies a very large space. Also it is necessary in order to guide the threads or bands positively through the various baths to exert a certain amount of draught which in many cases is not desirable and, indeed, is often injurious. On the guide rollers or other forwarding devices that may be used the threads or bands frequently suffer damages of various kind.

Reference is made to the accompanying drawings, the Figure 1 of which shows a sectional view of an apparatus used for the process of the present invention. Figure 2 shows a plan view of the rotating table on which the fiber material is laid.

Figure 3 is a sectional view of an apparatus used for the process with means for imparting a to and fro movement to said apparatus.

It is the object of the present invention to avoid these difficulties in a simple manner very economical to space by subjecting the freshly spun material without tension and at any suitable temperature in wetted condition or immersed in liquid to the desired individual treatments. The invention consists of a system for this purpose and may be described as follows:

55 In spinning, for example, cellulose wool, by a

viscose process, the freshly precipitated bundle of fibers is guided over a roller or similar device and is laid after a short suspension path on a support which is rotating about a vertical or slightly inclined axis, advantageously a slowly rotating plate. It is of advantage to lay the bundle on the plate in a form which fills the plane as much as possible, for instance in a zig-zag form, by moving it to and fro, or in a spiral form. In this manner it becomes possible to bring onto a plate of 1 meter to 1.2 meter diameter, rotating once per minute, 100 meters or more of the band. If the fibers are still acid after the spinning, it generally suffices to retain them for a time corresponding with the 100 meters on the rotating plate in order that the decomposition of the residual xanthate may be complete. The bundles of fibers is then led, if desired with simultaneous pressure, over a further roller onto a second, third, fourth and if necessary still further rotating plates, on each of which as may be desirable the thread is subjected to the necessary step of the treatment, the threads being simultaneously pressed once or more often on the rotary plate. If desired the plates may be perforated, in which case the fibers may easily be washed on the plate by slow sprinkling with water of the desired temperature. If desired the washing process may be reinforced or accelerated by squeezing the fibers. For this purpose there may be arranged under the perforated rotary plate, particularly under the last part of it, a suction device. If the rotary plate is embedded in a closed casing, the cellulose wool may be subjected to a treatment with gas or vapor at any desirable stage.

If the rotary plate has a rim, the cylindrical hollow space thus provided may serve as a bath and the fibrous bundle may be laid in this bath in the manner described above. To obtain constant working the liquid may be allowed to flow through the bath or if the fiber consumes a chemical in the operation such chemical may be introduced into the bath in a proportion to keep the strength thereof constant.

The process of the invention is applicable also to the treatment of cut fibers. These are laid upon the rotary plate by a depositing device and after treatment are removed by a lifting device and transported further.

The system is extraordinarily simple. It requires, for example, a space of 10 meters long, whereas in the known systems the length must be 100 meters and more. The particular advantage of the system resides in the fact that it

can be constructed remarkably easily in a closed housing of comparatively small over-all dimensions. Thus it becomes possible to treat the material with great uniformity before, during and after the decomposition of the xanthate and also during the whole washing process, with gases and vapors.

One modification of applicants' present invention has been shown in the accompanying drawings. The fiber bundle is laid at A on the support C rotating in direction of the arrow in zig-zag form. In order to facilitate the understanding of the drawings the single layers have been shown in rather large distance. After a rotation till up to 360° the fiber is taken off from the rotating support at E. In order to obtain the zig-zag movement of the fiber bundle a reciprocating movement is imparted either to the galette from which the fiber is falling on to the rotating plate or to the rotating plate itself.

Figure 3 shows a device in which the whole rotating support is moved to and fro. The device shown in Figures 1 and 2 is arranged on a chassis ch supported on the wheels y and moving on the rail x. The device is only partly shown in Figure 3, the bell H and part of the support C being shown. The rest of the mechanism is the same as in Figure 1. The motor m serves to drive the rotating plate by means of the cogged wheels v. The whole arrangement is moved to and fro in the direction of the arrows by the wheel wh which is connected therewith by the rod r₁ which is connected to the turning points p₃ and p₄.

By means of the rims a and b an annular ring is separated from the plate on which the fiber bundle is laid and on which a series of rollers W are acting. Between the rollers the sprays D are located. By arranging several sets of rollers and sprays one after the other different after-treating processes may be carried out simultaneously. The fiber material is impregnated by the sprays with the treating liquids and squeezed by the rollers which are driven by adhesion to the rotating plate. Behind each roller when looking in direction of the arrow a spray may be arranged which on this side moistens the roller and thereby prevents a sticking of the squeezed dried material to the roller.

The squeezed-off treating liquid runs either through the perforations c arranged at the side of the rollers, or in the case the plate is perforated in sieve-like manner, through the perforations d into the receiving device, for instance F. The treating liquid may also be sucked off by means of a suction device G as it is shown on the right-hand side of the drawing. Such a receiving device is arranged for each treating or washing liquid beneath the corresponding spot of the rotating plate. The spraying devices are present in a corresponding number. The wash-

ing liquids, for instance water or different treating liquids are circulated through the spraying devices. Instead of fiber bundles also cut staples may be after-treated on this apparatus if a cutting device is arranged before E.

The whole rotating plate may be put into a bell H which at J is connected with a suction device so that detrimental gases may be removed. Gases or vapors may be introduced through the opening K so that also an after-treatment of the fiber with these latter may be carried out. The bell H has only been shown in a diagrammatic manner.

What we claim is:

1. A device for the continuous treatment of threads which comprises a plate rotating about a substantially vertical axis, means for laying the threads onto said plate in zig-zag form, means for impregnating the threads with treating agents, means for removing said treating agents, and means for continuously withdrawing said threads from said plate. 15

2. A device for the continuous treatment of threads which comprises a plate rotating about a substantially vertical axis, means for laying the threads onto said plate in zig-zag form, means for impregnating the threads with treating liquids on said plate, means for removing said treating liquids, and means for continuously withdrawing said threads from said plate. 25

3. A device for the continuous treatment of threads which comprises a plate rotating about a substantially vertical axis, means for laying the threads onto said plate in zig-zag form, means for impregnating the threads with treating gases on said plate, means for removing said treating gases, and means for continuously withdrawing said threads from said plate. 35

4. A device for the continuous treatment of threads which comprises a plate rotating about a substantially vertical axis, means for laying the threads onto said plate in zig-zag form, sprays above said plate for impregnating the threads with treating liquids, squeezing rollers pressing on the plate for removing said liquids, and means for continuously withdrawing said threads from said plate. 40

5. A device for the continuous treatment of threads which comprises a plate rotating about a substantially vertical axis, said plate being perforated in sieve-like manner, means for laying the threads onto said plate in zig-zag form, sprays above said plate for impregnating the threads with treating liquids, squeezing rollers pressing on the plate, a suction device for removing said treating liquids, and means for continuously withdrawing said threads from said plate. 50
